CHARLES C. RIEFSNYDER

By Earl M. Sinclair, Atty.

UNITED STATES PATENT OFFICE.

CHARLES C. RIEFSNYDER, OF DES MOINES, IOWA, ASSIGNOR OF ONE-HALF TO JOHN McCRAY, OF DES MOINES, IOWA.

LINK.

1,195,268.

Specification of Letters Patent.

Patented Aug. 22, 1916.

Application filed February 13, 1914. Serial No. 818,554.

To all whom it may concern:

Be it known that I, CHARLES C. RIEFSNYDER, a citizen of the United States of America, and resident of Des Moines, Polk county, Iowa, have invented a new and useful Link, of which the following is a specification.

The object of this invention is to provide improved means for detachably yet securely fastening one object to another, such as a shipping-tag to a container.

A further object of this invention is to provide an improved link formed with interengaging hooks.

15 My invention consists in the construction, arrangement and combination of elements hereinafter set forth, pointed out in my claims and illustrated by the accompanying drawing, in which—

20 Figure 1 is an elevation illustrating my improved device in use to secure a shipping-tag to a milk-can. Fig. 2 is an elevation of the link detached, on an enlarged scale. Fig. 3 is a detail elevation of the interengaging hooks, on a further enlarged scale.

25 In the construction and application of the device the link is formed of a rectangular loop 10 of suitable material such as round spring wire and the ends of the wire are formed with interengaging hooks 11, 12. Straight end portions 15, 16 of the wire are arranged in alining relation to and from one end of the rectangle and terminate in the hooks 11, 12, to which they are joined by integral inclined portions 17, 18 crossing each other at right angles. The hook 11 is

30 preferably in the form of a half-circle having an internal diameter equal to the diameter of the wire and adapted to embrace the straight end portion 16 adjacent the hook 12, and the hook 12 may describe one-fourth of a circle or be somewhat less than a half-circle having the same radius and adapted to cross beneath and engage

35 the straight end portion 15 adjacent to the hook 11, so that when engaged as shown the ends of the loop are securely held against accidental detachment. The radii of the hooks 11, 12 are parallel with each other

40 and at right angles to the plane common to the straight end portions 15, 16. I prefer to make the engagement of the hooks 11, 12 such that they cannot be disengaged manually with the bare hands but will require the

use of an extraneous instrument such as a 55 pair of pliers, applied torsionally of the end portions 15, 16 to spring the hooks away from the portions engaged thereby coincidentally for the removal of the link. The link may be employed for the purpose of 60 securely yet removably attaching a device such as a shipping-tag 13 to a container such as a milk-can 14, or for any other suitable purpose.

The use of this device will be found quite 65 convenient especially for the purpose described and will absolutely prevent all accidental removal of the tag and will tend to prevent meddling therewith because of the difficulty of opening the link with the bare 70 hands. The hooks on each end of the loop embrace the opposite end of the loop adjacent its hook, and when sprung into place will firmly hold said loop in closed position.

I claim as my invention—

75 1. As an improved article of manufacture, a link formed of a single length of round spring wire bent into substantially rectangular form, straight end portions of the wire being in a common plane longitudinally to form one end of the rectangle, said straight end portions of the wire terminating in hooks midway of said end of the rectangle, said hooks being joined to the straight end portions by integral inclined 80 portions, one hook describing one-half of a circle having an internal diameter equal to the diameter of the wire and adapted to embrace one straight end portion of the wire adjacent the other hook, said other hook describing one-fourth of a circle of the same 85 radius and adapted to engage the first straight end portion of the wire adjacent the first hook, the radii of said hooks being in parallel planes at right angles to the plane 90 common to the straight body portions.

2. As an improved article of manufacture, a link formed of a single length of round spring wire bent into substantially rectangular form, straight end portions of the wire 100 being in a common plane longitudinally to form one end of the rectangle, said straight end portions of the wire terminating in hooks midway of said end of the rectangle, said hooks being joined to the straight end 105 portions by integral inclined portions crossing each other at right angles, one hook describing one-half of a circle having an

internal diameter equal to the diameter of the wire and adapted to embrace one straight end portion of the wire adjacent the other hook, said other hook describing 5 one-fourth of a circle of the same diameter and adapted to engage the straight end portion of the wire adjacent the first hook, the radii of said hooks being in parallel

planes at right angles to the plane common to the straight body portions. 10

Signed by me at Des Moines, Iowa, this ninth day of February, 1914.

CHARLES C. RIEFSNYDER.
